(57) **CLAIM**

The ornamental design for a hair straightener, as shown.

DESCRIPTION

FIG. 1 is a top, front and side perspective view of a hair straightener showing my new design;

FIG. 2 is a side elevational view thereof;

FIG. 3 is a side elevational view thereof from the side opposite that shown in FIG. 2;

FIG. 4 is a top plan view thereof;

FIG. 5 is a bottom plan view thereof;

FIG. 6 is a front elevational view thereof;

FIG. 7 is a rear elevational view thereof;

FIG. 8 is a top, front and side perspective view of a hair straightener showing the second embodiment of my new design;

FIG. 9 is a side elevational view thereof;

FIG. 10 is a side elevational view thereof from the side opposite that shown in FIG. 9;

FIG. 11 is a top plan view thereof;

FIG. 12 is a bottom plan view thereof;

FIG. 13 is a front elevational view thereof; and,

FIG. 14 is a rear elevational view thereof.
